UNITED STATES PATENT OFFICE.

ROBERT MORSE WITHYCOMBE, OF SYDNEY, NEW SOUTH WALES, AUSTRALIA.

BATH SPRAY BRUSH.

Application filed March 31, 1925. Serial No. 19,708.

This invention relates to bath spray brushes and has for its principal object the construction of an improved brush of the fountain type in which the paths of the jets 5 of liquid emanating from the perforations in a central reservoir are intersected by the inner layer or layers of the filamentous portion of the brush so that the jets are transformed into numerous films upon the surfaces of the filaments, avoiding the direct 10 impingement of the jets upon the body to which the brush is applied, thereby preventing splashing, and at the same time constantly flushing the filamentous portion and 15 being supplied without waste between the contacting surface of said filamentous portion and the body, where the cleansing action is taking place.

Another object of the invention is to construct a brush in which a central reservoir or "rose" is surrounded by a helically wound strip of rubber or the like cut transversely along one edge to form filaments and wound under tension so that the several layers of 20 the helical winding stand away from each other, the innermost layer assuming a conical shape, a similar shape being also assumed by the successive layers in a progressively less degree until the outer layer 25 is reached, the latter being substantially cylindrical and giving conventional shape to the brush.

Other objects of the invention will appear as the description of a preferred embodiment thereof proceeds.

In the drawings:—

Figure 1 is a view in elevation showing my improved bath spray brush.

Figure 2 is a diametrical section on the line 2—2, Figure 1.

Figure 3 is a section taken along the line 3—3 of Figure 2.

Referring now in detail to the several figures, the numeral 1 represents a reservoir or "rose" which is preferably metallic and provided with a tubular portion 2 intended to be connected by a flexible tubing 3 or other suitable means with a source of water, preferably under pressure. The face of the reservoir is perforated as indicated at 4. The reservoir is surrounded by a strip 5 of rubber or other material, preferably elastic, wound helically to form several layers as indicated at 6 in Figure 2. Slits are made in one longitudinal edge of the strip 5 to form bristles or filaments 7. The perforated

face of the reservoir 1 is bevelled at its edge, as at 10, and the strip 5 is wound under tension around the periphery of the reservoir with the inner ends of its slits substantially 60 in alignment with said perforated face; and, since the slotted portion of the innermost layer is not under such restraint as the unslotted portion of said layer, the filaments 7 of said innermost layer will be drawn inwardly over the bevelled edge 10 of the perforated face of the reservoir and be caused to assume a conical form as shown at 8 in Figure 3. Under the same or a less degree of tension as may be found desirable, the 70 succeeding layers are wound so that the filament 7 thereof will assume less degrees of conicity until the outer layer is reached wherein both the filaments and the unslotted portion will be substantially cylindrical, that 75 is to say, normal to a plane perpendicular to the axis of the brush.

Any desired means may be employed for securing the rubber strip to the peripheral edge of the reservoir, in the present instance said reservoir being shown as formed with a shallow annular channel 9 into which the upper edge of the unslotted portion of the rubber sinks under the tension of winding, automatically interlocking itself with 80 said reservoir sufficiently to avoid subsequent displacement. Any suitable cement may be applied to the unslotted portion of 85 said rubber strip to promote adhesion of the successive layers and it may be desirable 90 to apply a vulcanizing cement thereto and to vulcanize the brush so that the inner ends of the helical windings become unitarily massed. This may be done by immersing 95 the brush in boiling water for a suitable length of time.

A brush formed according to the principles of the present invention has the following advantages; the innermost layer of filamentous material intersects the paths of 100 the jets emanating from the perforations 4. It thus transforms the jets into films which flow along the rubber filaments and are delivered to the body as films and not as jets, thereby avoiding splashing. The separated 105 relationship assumed by the successive layers of filaments assures that the brush may be easily dried and maintained in sanitary condition and the decreasing conicity of the several layers, and particularly the cylindrical form of the outermost layer, gives to 110 the brush a conventional shape and causes

it to have an appearance of great fullness, notwithstanding the use of a minimum length of the rubber strip.

While I have above described what I believe to be a simple and practical embodiment of my invention yet it is to be understood to be within the scope of the invention to vary the details of construction or the shape and arrangement of the parts, being restricted only by the express limitations defined in the appended claims.

Having described my invention what I claim as new and desire to secure by Letters Patent, is:—

1. A bath spray brush comprising a rose having a face bevelled at its edge and provided with jet perforations, filamentous layers helically wound around the periphery of said rose and drawn inwardly over the bevelled edge of said face into substantially conical form, the innermost layer intersecting the paths of jets of liquid emanating from said perforations.

2. A bath spray brush comprising a rose having a face bevelled at its edge and provided with jet perforations, helically disposed filamentous layers surrounding said face and engaging the periphery of said rose under tension with one end projecting beyond said perforated face over the bevelled edge of said face whereby the innermost layer is caused to assume a substantially conical form intersecting the paths of jets of liquid emanating from said perforations.

3. A bath spray brush comprising a rose having a face bevelled at its edge and pro-

vided with jet perforations, helically disposed filamentous layers surrounding the periphery of said rose under suitable tension with one end projecting beyond said face and with the projecting ends of the innermost layer drawn inwardly over the bevelled edge of said face into a substantially conical form and intersecting the paths of jets of liquid emanating from said perforations with the projecting ends of the intermediate layers assuming conical forms of progressively less conicity and the projecting end of the outermost layer substantially normal to a plane perpendicular to the axis of said rose.

4. A bath spray brush comprising a rose having a face provided with jet perforations and bevelled at its edge, a strip having filament forming slits in one of its longitudinal edges, said strip being helically wound upon itself under tension around the periphery of said rose with its slitted portion projecting beyond said face and drawn inwardly over the bevelled edge of said face to assume a substantially conical shape, said rose having a depression around its periphery with which the unslotted portions of said layers interlock under tension to prevent their displacement relative to said rose, the slotted portion of the innermost layer intersecting the paths of jets of liquid emanating from said perforations.

In testimony whereof I have hereunto set my hand.

ROBERT MORSE WITHYCOMBE.
